Patented May 7, 1918.

Inventor:
Warren G. Daniel.
By Jas. L. Sweet, Atty.

UNITED STATES PATENT OFFICE.

WARREN G. DANIEL, OF BOONE, IOWA.

DESIGN FOR A BADGE OR EMBLEM.

52,004.

Specification for Design.

Patented May 7, 1918.

Application filed October 16, 1917. Serial No. 197,372. Term of patent 14 years.

To all whom it may concern:

Be it known that I, WARREN G. DANIEL, citizen of the United States of America, and resident of Boone, Boone county, Iowa, have invented a new, original, and ornamental Design for a Badge or Emblem, of which the following is a specification, reference being had to the following drawing.

The object of this invention is to provide an ornamental design for badges or emblems.

The figure is a face view of a badge or emblem, showing my new design.

I claim:

The ornamental design for a badge or emblem, as shown.

WARREN G. DANIEL.
